UNITED STATES PATENT OFFICE.

JOSEPH P. LANDRY, OF UXBRIDGE, MASSACHUSETTS.

TAKE-UP MECHANISM FOR LOOMS.

1,182,574.

Specification of Letters Patent.

Patented May 9, 1916.

Application filed October 2, 1912. Serial No. 723,509.

To all whom it may concern:

Be it known that I, JOSEPH P. LANDRY, a citizen of the United States, and resident of Uxbridge, in the county of Worcester and 5 State of Massachusetts, have invented certain new and useful Improvements in Take-Up-Mechanism for Looms, of which the following is a specification.

This invention relates to the means for operating the take-up rolls of looms, and the object of the invention is to provide means for preventing the weaver or operative from attempting to hasten the production of fabric by manually advancing the take-up roll. 10 This operation is commonly known as "pumping", and it of course results in the production of imperfect goods, which may not be discovered until after the goods have been sold. As will be explained hereinafter, 15 I have provided means which renders it absolutely impossible for the weaver to "pump" when the loom is operating, the lock which prevents such pumping being capable however of being released or unlocked when the 20 loom is stationary and when it becomes necessary to slack back to pick out.

The invention consists in the construction and combination of parts substantially as hereinafter described and claimed.

30 Of the accompanying drawings: Figure 1 is an end elevation of a portion of a loom embodying my present improvements; Fig. 2 is an elevation from the right of Fig. 1; Fig. 3 represents a section on line 3—3 of Fig. 2. Fig. 4 is a detail elevation, partly in section, on line 4—4 of Fig. 3.

Similar reference characters indicate the same or similar parts in all of the views.

A portion of the frame of the loom near 40 the base and at the left hand thereof is indicated at 10. The vertical shaft 11, while not the power shaft of the loom, is the driving shaft for the mechanism hereinafter described. Said shaft 11 is provided with bevel pinions 12, 13 loose on said shaft. Meshing with said pinions is a suitably mounted bevel pinion 14, compounded with which is a gear 15 meshing with a gear 16 carried by the shaft 17. Splined on the 45 shaft 11 is a clutch member 18 carried by a

vertically adjustable rod 19, said clutch member 18 alternately coöperating with clutch members carried by the bevel pinions 12, 13. By shifting said clutch member 18, the direction of rotation imparted to the 55 shaft 17 may be reversed. As this reversing mechanism forms no part of my present invention, further description or illustration thereof is not necessary.

The shaft 17 carries the bevel pinion 20 60 meshing with a bevel pinion 21 carried by a shaft mounted in a bearing 22, said shaft having a worm 23 meshing with a worm gear 24 carried by a shaft 25. So far as the present invention is concerned, any mechanism 65 for reversing the direction of rotation of the worm 23 might be substituted for the reversing mechanism 11, 12, 13, *et seq.* A sprocket 26 carried by shaft 25 is connected by a chain 27 with a sprocket 28 carried by a 70 clutch member 29 (Figs. 1 and 2) loosely mounted on shaft 30. Said shaft has a hand wheel 31 at its outer end, and at its inner end is connected through suitable gearing 32, such as the usual gearing, with the "sand 75 roll" 33 and "floss roll" 34 of the usual or any preferred construction. It is to be understood at this point that it is by means of the hand wheel 31 that the rolls 33, 34 are to be operated when necessary to slack back 80 the warp for any purpose, such as picking out.

Splined on the shaft 30 is a clutch member 35 adapted to coöperate as hereinafter described with the clutch member 29, said 85 clutch member 35 having a hub 36 having a groove engaged by a yoke 37 carried by a lever 38 pivoted at 39 to a bracket 40 (Figs. 2, 3 and 4). The lever 38 has a lug 41 engaging a notch 42 in a disk 43 carried by a 90 hub 44 mounted on a pin or stud shaft 45 mounted in an ear or ears 46 of the bracket 40. A coil spring 47 is connected at one end to an ear 46 and at the other end to the disk 43, so as to have a normal tendency to 95 hold the disk 43 in the position shown in Figs. 2 and 4 with the clutch members 29, 35 interengaged. A fixed stop 48 coöperates with the shoulder 49 of the disk 43 to hold the disk in the position just explained. The 100

disk 43 is provided with another shoulder 50 which is engaged by a lock arm 51 carried by a hand lever 52, the latter being secured to the usual control shaft 53, said shaft in practice extending from one end to the other of the loom and having at each end a hand lever, such as the hand lever 52, by means of which the starting and stopping of the loom can be effected.

10 It is to be understood that the loom is supposed to be in operation when the hand lever 52 is in the position shown in Fig. 1, the lock 51 being then in position to coöperate with the shoulder 50 of the disk 43 so as 15 to prevent rotation of said disk in the direction of the arrow, Fig. 4. The hub 44 of the disk is provided with a hand wheel 54, by means of which, after the lever 52 has been moved to stop the loom and carry the 20 lock arm 51 away from the shoulder 50, the disk can be rotated in the direction of the arrow, Fig. 4, so as to oscillate the lever 38 and separate the clutch member 35 from the clutch member 29. At this time the hand 25 wheel 31 may be operated to manually actuate the take-up roll. The loom cannot be started again until the hand wheel 54 is released, because the portion of the disk 43 behind the shoulder 50 will oppose the 30 turn of the arm 51 to the position shown in Fig. 3. When the hand wheel 54 is released the spring 47 returns the disk with its shoulder 49 against the stop 48, thus returning the lever 38 to the position shown in Fig. 4 35 and reengaging the clutch members 35, 29. It is impossible then for the weaver to manually actuate the hand wheel 31, because the worm 23 engaging the gear 24 acts through the sprockets and the chain 27 to prevent the movement of said hand wheel. Without this worm gear lock to prevent back motion, or its equivalent, the hand wheel 31 might be operated after putting the clutch member 18 in an intermediate position.

40 When the weaver finds it necessary to tighten or slacken the warp, he must operate the hand wheel 54 with one hand to release the lock, and then with the other hand operate the hand wheel 31. But he cannot 45 operate the hand wheel 54 so as to release the lock excepting when the loom is stationary. Therefore he cannot perform the operation known as "pumping" to increase the apparent length of woven fabric.

50 Having described my invention, I claim:

1. A loom having take-up mechanism arranged to permit manual operation of the take-up roll when the loom is stopped, and means lockable for preventing manual operation of the take-up roll when the loom is in motion, said means being arranged to be locked by a locking member movable to locking position by the shipping lever when the latter is moved to start the loom, said

locking member being arranged so as to be incapable of removal from locking position until the shipping lever is moved toward stopping position.

2. A loom having take-up mechanism arranged to permit manual operation of the take-up roll when the loom is stopped, and means for preventing manual operation of the take-up roll when the loom is in motion, said means being arranged to be locked by a member rigidly affixed to the shipping lever, and to be released only by movement of the shipping lever toward stopping position.

3. A loom having a take-up mechanism operating shaft, a clutch member loose on said shaft, means for driving said clutch member, a clutch member connected to said shaft to rotate the latter, means for shifting the last mentioned clutch member to and from the loose clutch member, and lock mechanism for preventing such shifting, said lock mechanism being connected with and actuated by the loom starting and stopping mechanism.

4. A loom having a take-up mechanism operating shaft, a clutch member loose on said shaft, means including a worm gear for driving said clutch member, a clutch member connected to said shaft to rotate the latter, means for shifting the last mentioned clutch member to and from the loose clutch member, and lock mechanism for preventing such shifting, said lock mechanism being connected with and actuated by the loom starting and stopping mechanism.

5. A loom having a take-up mechanism operating shaft, a clutch member loose on said shaft, means for driving said clutch member, a clutch member connected to said shaft to rotate the latter, means for shifting the last mentioned clutch member to and from the loose clutch member, lock mechanism for preventing such shifting, and a lever for operating the starting and stopping mechanism of the loom, said lock mechanism being connected with said lever.

6. A loom having a manually operable shaft connected to the take-up mechanism, separable clutch members on said shaft, one being loose and the other splined thereon, power driving mechanism for the loose clutch member, a lever for operating the starting and stopping mechanism of the loom, and lock-controlled means for shifting the splined clutch member, a part of said lock-controlled means being connected with said lever.

7. A loom having a manually operable shaft connected to the take-up mechanism, separable clutch members on said shaft, one being loose and the other splined thereon, power driving mechanism for the loose clutch member, a lever connected to the

splined clutch member for shifting it, said lever having a lug, a manually operable disk having a recess engaging said lug, and means connected with the starting and stopping mechanism of the loom and having a lock to prevent movement of said disk.

In testimony whereof I have affixed my signature, in presence of two witnesses.

JOSEPH P. LANDRY.
